UNITED STATES PATENT OFFICE.

JOSEPH KAHN, OF CHICAGO, ILLINOIS.

LOOSE-LEAF-BINDER LOCK.

Application filed June 3, 1926. Serial No. 113,401.

This invention relates to a loose-leaf binder lock.

One of the objects of the present invention is to provide a simple and inexpensive 5 lock for loose-leaf binders.

Another object of the invention is to provide an improved form of lock for loose leaf binders which is made up of two flat metal strips operatively connected together, in 10 which one moves transversely with respect to the other for securing the binder lock.

Still another object of the invention is to provide an improved and novel form of 15 adjustable binder post in combination with my loose-leaf binder lock.

These and other objects of the invention are accomplished by construction and combination of the various parts in the manner hereinafter described and particularly pointed 20 out in the appended claims.

Referring to the drawings:

Fig. 1 is a top plan view of a loose-leaf binder with the top cover removed therefrom showing my improved loose-leaf binder 25 lock embodied therein,

Fig. 2 is a side elevational view of the loose-leaf binder shown on Fig. 1,

Fig. 3 is a fragmentary transverse cross-sectional view taken on the line 3—3 of Fig. 30 1 and showing the binder post adjusted to its smallest size,

Fig. 4 is a fragmentary transverse cross-sectional view showing the binder post adjusted to its longest position, and

Fig. 5 is a fragmentary top plan view of a loose-leaf binder showing a modified form 35 of the loose-leaf binder lock.

In illustrating one embodiment of my invention, I have shown the same in connection 40 with a loose-leaf binder of which a fragmentary portion is shown in the drawing and is generally referred to by the reference character 10. This loose-leaf binder comprises the usual oppositely disposed front cover 11 and rear cover 12 which in turn are joined 45 together by a flexible back, as shown at 13. These covers 11 and 12, as well as the back 13, may be formed of paper, leather, or imitation leather, or any other suitable material 50 of which such binders are made.

The loose-leaf binder is provided with the usual flies or flaps 14 and 15 which are reinforced with stiffening and flexibly connected to the back, as shown at 16 and 17, 55 adjacent the front and rear covers respectively. Secured to the flap 14 adjacent the

rear cover 12 is a reinforcing strip 18 which is preferably made of metal. This metal strip 18 extends substantially throughout the length of the binder and is secured to the flap 14 by means of rivets 19. Secured to the flap or fly 15, on the side thereof, adjacent the front cover 11, is a metal strip 20, the securing being also by means of rivets 21. The metal strip 20 extends substantially 60 throughout the length of the loose-leaf binder and is provided adjacent its ends with downwardly projecting lugs 22 which are preferably formed by pressing a portion of the metal of the strip outwardly. 70

One of the essential features of my invention is the provision of a novel form of adjustable binder post which is made of three pieces and which, when assembled, may be adjusted from one extreme position to the 75 other extreme position or from the position shown in Fig. 3 to the position shown in Fig. 4. This novel binder post comprises a threaded shank 22', of which there are two 80 in number, secured to the metal strip 18, by 85 having the head thereof riveted in a tapered aperture, as shown at 23. Mounted in threaded engagement with the threaded shank 22' is a sleeve 24 which is provided adjacent its lower end with a threaded portion 25. In order to secure the sleeve 24 from disengagement with the shank 25, after 90 the sleeve is mounted on the shank, I upset the upper end of the shank, as shown at 26, so that when the sleeve reaches the upper 95 end of the shank, or the position shown in Fig. 4, the sleeve is prevented from disengagement with the shank.

Mounted in the upper end of the sleeve 24 is an extension 27 which is provided with 100 a cylindrical projection 28 which is adapted to fit in the upper end of the sleeve. The extension 27 is secured to the sleeve by soldering the same thereto or by any other suitable means.

Formed integrally with and extending 105 upwardly from the extension member 27 is a cylindrical projection 29 which is preferably provided with a transverse slot, as shown at 30, on one side thereof. This slot 30 is adapted to engage the locking member in a manner hereinafter described. The strip 20 is provided with apertures as shown at 20' for the reception of projections 29 of the binder posts 24. Mounted for transverse movement on the metal strip 20 is a locking member or strip 31 which is provided with a 110

cutaway portion 32 which is located substantially midway between its ends to afford a finger grip for actuating the locking member.

5 The locking member 31 is guided in its transverse movement on the strip 20 by having its opposite ends provided with spaced-apart extensions 33 and 34 respectively. These spaced-apart extensions are bent 10 downwardly and inwardly so as to embrace the opposite ends of the metal strip 20 as shown at 35. The extensions 34 on the opposite ends of the locking member 31 are adapted to engage the lugs 22 formed on the 15 opposite ends of the metal strips 20 for limiting the transverse movement of the locking member with respect to the strip 20 and prevents its displacement therefrom. The locking member 31 is provided with transverse slots as shown at 36 so as to accommodate the heads of the rivets 21 in the transverse movement of the locking member 31. The locking member is provided with spaced-apart locking slots generally referred to by the character 37. These slots 20 37 are provided with a substantially transverse straight edge 38 which engages the periphery of the projection 29 on the outer side of each. The other or inner edge of 30 each of the locking slots 37 is provided with a transverse straight edge 39 adjacent the inner edge of the slot and also a curved portion as shown at 40 adjacent the outer edge of the slot. This transverse edge of 35 the locking slots 37 is adapted to engage the transverse groove 30 formed in the extension 29 for locking the locking member to the binder posts.

From this construction, it will be readily 40 seen that when the locking member is moved transversely on the metal strip 20 to a position in which the extensions 34 engage the lugs 22, the edges 39 of the locking slots 37 will be disengaged from the grooves 30 of 45 the binding posts and thereby permit the metal strip 20 to be disengaged from the binder posts so that the loose leaves may be removed or replaced.

In the modified form shown in Fig. 5, the 50 locking member 31^a is adapted to be moved in a direction reverse from that shown in Fig. 1 and is prevented from disengagement with the metal strip 20, by having transverse slots 41 formed in the opposite ends 55 thereof. Mounted in the transverse slots and secured to the metal strip 20 are rivets 42 which are provided with enlarged heads so as to prevent displacement of the locking member from the metal strip. These rivets 60 however, are sufficiently spaced from the metal strip as to permit the locking member to move with respect to the metal strip under a slight pressure. The binder posts 43 in this modified form, are provided with 65 peripheral grooves 44 adjacent their upper

ends and are adapted to receive the U-shaped edges 45 formed in the locking member 31^a for securing the locking member to the binder posts.

While in the above specification I have 70 described one embodiment which my invention may assume in practice, it will, of course, be understood that the same is capable of modification and that modification may be employed without departing from 75 the spirit and scope of the invention as expressed in the following claims.

What I claim as my invention and desire to secure by Letters Patent is:

1. In combination with a loose-leaf binder 80 cover, a pair of strips secured to the said binder cover, binder-posts secured to one of said strips, the second of said strips being adapted to engage said binder posts, and means movable transversely on said second-named strip for locking said loose-leaf 85 binder.

2. In combination with a loose-leaf binder 90 cover, a pair of strips secured to the said binder cover, binder posts secured to one of said strips, the second strip being adapted to engage said binder posts, and means engageable with and movable transversely on said second-named strip for locking said loose-leaf 95 binder.

3. In combination with a loose-leaf binder 100 cover, a pair of strips secured to the said binder cover, binder posts secured to one of said strips, the second strip being adapted to engage said binder posts, and a locking member movable transversely on said second-named strip for locking said loose-leaf 105 binder.

4. In combination with a loose-leaf binder 110 cover, a pair of strips secured to said binder cover adjacent to the front and rear cover members, binder posts secured to one of said strips and adapted to be engaged with the other of said strips, and means movable transversely on said last-named strip for locking said loose-leaf 115 binder.

5. In combination with a loose-leaf binder 120 cover, flaps formed integrally with said binder cover and positioned adjacent the front and rear cover members thereof, metal strips secured to said flaps, binder posts secured to one of said metal strips, there being apertures in the other of said strips adapted to receive said posts, means transversely movable on said last-named strip for engaging said posts for locking said posts to said strip, and means formed on said last-named strip for guiding said first-named means in its movement on said strip.

6. In combination with a loose-leaf binder 125 cover, metal strips secured adjacent the front and rear cover members thereof, two spaced-apart adjustable binder posts secured to one of said strips, each of said binder posts having a transverse recess formed on one side 130

thereof, the other of said metal strips having apertures therein for receiving said binder posts, a locking member having transverse slots therein on said other strip and adapted 5 to move transversely with respect thereto whereby the edges of said transverse slots engage the recesses in said binder posts for locking said loose-leaf binder.

7. In combination with a loose-leaf binder 10 cover, comprising front and rear cover members, metal strips secured to said cover adjacent said front and rear cover members, adjustable binder posts comprising threaded shanks secured to one of said strips, a sleeve 15 having a threaded portion engageable with said threaded shanks, an extension secured to said sleeve having a transverse slot formed on one side thereof, the metal strip secured adjacent said front cover having apertures 20 adapted to receive the extensions of said binder posts, a locking member mounted on the metal strip adjacent said front cover and movable transversely with respect to said strip and engageable with said extensions 25 for locking said loose-leaf binder.

8. In combination with a loose-leaf binder

cover comprising front and rear cover members and a transverse back, flaps secured to said binder adjacent said front and rear covers, metal strips extending longitudinally 30 of said binder and secured to said flaps, adjustable binder posts comprising threaded shanks secured to one of said metal strips, a sleeve having the lower end threaded and in engagement with said threaded shank and 35 the upper end of said threaded shank being upset to prevent displacement of said sleeve with respect to said shank, an extension having a transverse slot on one side thereof secured to the upper end of said 40 sleeve, there being apertures in the other of said metal strips adapted to receive the extension of said binder post, and a transversely movable locking member mounted 45 on said other strip and adapted to engage the recesses formed in the extensions of said binder posts for locking said loose-leaf binder.

In witness of the foregoing I affix my signature.

JOSEPH KAHN.
